FIG. 8

Position main pattern on supporting board.
Put buckets on pattern and board.
Place top ring on pattern.
Fill in sand.
Put on cope.

FIG. 9

Reverse mold.
Remove supporting board.
Fill in sand.
Place drag in position.

FIG. 10

Reverse mold.
Remove cope.
Remove top ring.
Replace cope.

FIG. 11

Reverse mold.
Remove drag.
Remove main pattern.
Replace drag.

UNITED STATES PATENT OFFICE.

LEVI J. WING, OF EAST ORANGE, NEW JERSEY.

APPARATUS FOR MAKING MOLDS.

No. 907,212.

Specification of Letters Patent.

Patented Dec. 22, 1908.

Application filed February 23, 1907. Serial No. 358,797.

To all whom it may concern:

Be it known that I, LEVI J. WING, a citizen of the United States of America, and a resident of East Orange, county of Essex, New Jersey, have invented certain new and useful Improvements in Apparatus for Making Molds, of which the following is a specification.

The present invention relates to the art of molding, and has more particularly reference to an apparatus for forming a casting mold used to produce turbine wheels or other articles.

The object of the invention is to enable turbine wheels to be produced quickly and cheaply and consists of the hereinafter described features of construction.

In the said drawings:—Figures 1 and 2 are respectively a plan and a vertical sectional view of a temporary supporting board which may be and is employed in carrying out the invention. Fig. 3 is a plan view of the main pattern ring. Fig. 4 is a perspective view of a portion of the main pattern ring and of the auxiliary pattern ring. Fig. 5 shows one of the buckets. Fig. 6 is a plan view of the turbine wheel as produced by the herein described process. Fig. 7 shows a portion of this turbine wheel looking at the outer periphery thereof. Figs. 8, 9, 10 and 11 are vertical sectional views of the mold showing the several steps employed in the herein described process.

Similar characters of reference indicate corresponding parts in the several views.

1 indicates a temporary supporting board which is shown here as a plain wooden board having a central circular recessed portion 2. Surrounding the central recess are a plurality 40 of bucket spacing members 3 shown here as pins.

4 denotes the main pattern which is here shown as a circular ring. This main pattern is composed of a main portion 5, and a reduced portion 6 provided with the spacing members 7, whose outer periphery is flush with the outer periphery of the main portion. These spacing members extend only part of the way to the upper surface of the ring and 50 are adapted to support an auxiliary pattern 8, here shown in the form of a ring. When this auxiliary pattern is placed on the spacing members 7, a structure is produced whose configuration is that of the bucket supporting member to be cast.

The supporting board and the main pat-

tern ring are provided with coöperating registering members in the form of apertures 9 and lugs 10 so that when the main pattern is placed in position the spacing members on the board and on the main pattern will be in alinement.

The bucket is indicated by 11 and is provided with an impact surface 12 and with a tail 13. This bucket may be produced in any manner found suitable as by drop-forging or otherwise.

The mechanism for carrying out the process now being understood the process itself will be described.

The main pattern is placed on the temporary supporting board in such a manner that the bucket spacing members are in alinement. The buckets are then arranged circumferentially around the pattern on the board by inserting their tails 13 into the slots of the main pattern between the spacing members. The auxiliary pattern or top ring is then placed on the upper surface of the spacing members of the main pattern. The interior of the main pattern is then filled up with the body of sand indicated by 14 and the buckets are surrounded by the body of sand 15 on their upper side, which body of sand slopes downward toward the outer edge of the supporting board. One portion (here called a cope and indicated by 16) of the flask is now placed on top of the partially formed mold. The appearance of the parts after these steps have been taken is indicated in Fig. 8.

The mold is now reversed and the supporting board removed. The mold is completed by filling up with sand on the other side of the buckets in a manner similar to the body of sand indicated by 15. The other portion (here called a drag and indicated by 17) of the flask is now placed in position. These several steps are shown as having been completed in Fig. 9. The mold is reversed again, the cope is removed, the auxiliary pattern or top ring is removed and the cope is replaced. Part of the pattern has now been withdrawn. The result of these steps is shown in Fig. 10. The mold is reversed once more, the drag is removed, the main pattern is removed, and the drag is replaced. The complete withdrawal of the pattern leaves the buckets embedded in the mold and extending into the casting chamber 18. The metal is now poured and runs into the said casting chamber whereby a bucket supporting member 19 is cast on the

previously formed buckets, forming a structure shown in Figs. 6 and 7. The completed mold ready to be poured is shown in Fig. 11.

The drag is provided with a pouring gate 5 20 connected by channels 21 to a circumferential gutter 22 which communicates with the casting chamber of the mold by means of the ducts 23.

What is claimed is:—

10 In the system of casting one member on another and previously formed member, an apparatus for forming a casting mold comprising a main pattern provided with re-

cesses for the reception of the previously formed members, a temporary supporting 15 board for holding the main pattern and for supporting the previously formed members, and a top ring adapted to be placed over the main pattern.

Signed at New York city this 18th day of 20 February 1907.

LEVI J. WING.
